KNOCKDOWN BENT WOOD FURNITURE

Norman M. Kreizelman, Merrick, N. Y.

Application May 4, 1951, Serial No. 224,621

3 Claims. (Cl. 155—193)

1

This invention relates generally to knock down furniture; and, in particular, to articles having legs, such as chairs and chair frames.

The general object of the invention is to provide a novel, easily fabricated, and durable structure for a knock down article of furniture of the class described. The invention contemplates a structure which may be readily assembled and disassembled, and which, when knocked down, requires but little storage or shipping space. Basically the structure may comprise but three structural elements, suitably joined together, as by screws, and provides a main frame having four strong legs, which may be designed as a complete chair or as a frame especially useful in the manufacture of chairs.

A particular object of the invention is to provide a chair or chair frame of the knock down type having but three basic structural elements, each thereof being a single unitary piece of molded plywood made of multiple ply sheet stock bonded together with a suitable resin. These elements are adapted to be joined together to form a sturdy structure by as few as four screws. An advantage of the invention is the ease with which its few structural elements may be assembled by unskilled persons.

These and further objects and advantages of the invention will be more fully understood from the following detailed description and from the drawing, in which:

Fig. 1 is a perspective view of a chair frame constructed according to the invention;

Fig. 2 is a bottom plan view of the chair frame;

Fig. 3 is a perspective view of a chair constructed according to the invention;

Fig. 4 comprises bracketed side elevational views of the three structural elements of the chair frame of Fig. 1, these also being the basic elements of the chair of Fig. 3;

Fig. 5 is a perspective detail illustrating the manner in which the leg forming elements of the basic structure are joined; and

Fig. 6 comprises bracketed enlarged fragmentary details of two of the elements shown in Fig. 4.

The structure of the invention comprises essentially an article of furniture, or frame therefor, formed of two crossed U-shaped molded plywood elements each having a straight intermediate portion with these portions oppositely rabbeted whereby these elements may be fitted together to provide an X-shaped platform having flush upper and lower surfaces and supported, as by legs, by the extremities of the elements; and a

2

third molded plywood element detachably secured to the platform and thereby rigidly tying the structure together to form a sturdy construction.

As a chair or a chair frame the U-shaped elements constitute, together, four legs and a mount for the third element which may be not only a means for tying the structure together but may also serve as a seat, an integral seat and back rest, or as a bracket for a back rest to be mounted thereon.

The chair frame shown in Figs. 1 and 2 is typical of this structure. The frame shown here is also that employed in the chair of Fig. 3.

The chair frame of Figs. 1 and 2 comprises the three elements shown separately in side elevation in Fig. 4. These elements are all made of molded plywood sheet stock with the curved portions flatwise with respect to the plies; and preferably each element is formed of sheet stock having an odd number of plies with the grain of the plies being substantially parallel to the longitudinal axis of the element. See Fig. 6, in which portions of two of the elements of Fig. 4 are shown somewhat enlarged so that the disposition of the plies with respect to a molded curve may be seen. For clarity the plies are not indicated in figures other than the detailed Figures 5 and 6.

30 Two of the elements of Fig. 4, designated 10 and 11, are seen to be U-shaped, each having an intermediate straight portion 12, and depending and slanting extremities 13 and 14. The straight portion 12 of element 10 is provided with a rabbet 15 on the underside of the element; portion 12 of element 11 has a rabbet 16 on the upper side of the element. Fig. 5 is a fragmentary perspective detail of portions 12 of the elements 10 and 11 showing rabbets 15 and 16 and the manner 35 in which the elements are to be fitted together. It will be noted in Figs. 5 and 6 that five-ply wood is here used; the rabbets 15 and 16 are of equal depth, each extending from the normal surface plane of the element to the median plane of the middle ply. Thus when the elements 10 and 11 are fitted together an X-shaped platform, as shown mostly in dotted lines in Fig. 2, is provided, and both its upper and lower surfaces are flush. In the drawing the rabbets are assumed to cross 40 the longitudinal axis of the elements 10 and 11 at 90°; thus a foursquare arrangement of legs is provided as shown in Fig. 2. However, it will be understood that the rabbets may be formed at different angles if the arrangement of legs 45 is desired to be otherwise than shown. The legs 50

of the chair frame are formed of the depending and slanting extremities of the elements 10 and 11, extremities 13 being front legs, and extremities 14 being rear legs. The third element shown in Fig. 4, and designated 17, is here adapted to serve both as a tie for the structure and as a bracket or mount for a back rest to be applied to the frame. Element 17 comprises a generally L-shaped piece of molded plywood having a horizontal portion 18 adapted to be applied preferably to the underside of the X-shaped platform provided by the crossed elements 10 and 11, and so to function as a means for tying the structure together, as by means of the screws 19 shown in Fig. 2, and to prevent any angular wobbling of the legs; and an upwardly extending and suitably curved portion 20 upon which a back rest may be mounted.

Fig. 3 is a perspective view of a chair comprising the frame of Figs. 1 and 2, and, mounted thereon, a back rest 21 and a seat 22. The back rest 21 may be secured to portion 20 of element 17 as by screws; and the seat 22 may similarly be secured to the upper surface of the X-shaped platform. It is of course immaterial whether portion 13 of element 17 be applied to the top or the bottom of the X-shaped platform, for in either position portion 18 serves the same purpose. However, it is convenient that the portion 18 be secured to the bottom of the platform so that a flat bottom seat may be applied without special forming directly onto the smooth upper surface of the platform. However, the portion 18 may, if desired, be applied to the upper surface of the X-shaped platform. And it will be readily understood that element 17 may itself be designed to constitute a tie member, a seat, and a back rest; such modification merely requires that the horizontal portion 18 be of suitable relative size and be mounted on the upper side of the X-shaped platform; and that the upwardly extending portion 20 be sufficiently large and properly molded to conform comfortably to the user.

Fig. 4 is particularly indicative of the space-saving features of the basic structure when knocked down, while Fig. 2 shows how simply the structure may be locked together for use as an article of furniture.

The structure of the invention may be seen to have considerable flexibility as to design. Elements 10 and 11 may be of such ply widths and of such curvatures as desired, and element 17 may be of various widths and curvatures. Consequently, chairs of different appearance may be fabricated by utilizing chair frames constructed according to the invention. In the exemplary structure for a chair frame shown herein the elements 10 and 11 are seen to have extremities of equal length and slant so that the portions 12 of the elements are horizontal. However, if desired, elements having extremities or leg portions of different lengths and slants may be substituted, as, for example, where it is desired that the X-shaped platform be slanting, as from the front to the rear of the chair frame. The rabbits 15 and 16 are shown, for example, in Fig. 5 to be centrally located, as well as at 90° to the longitudinal axes of the elements, resulting in the arrangement of legs seen in Fig. 2. However, the rabbits may be provided off center and need not be normal to the longitudinal axes of the elements, as, for example, where it is desired that the front legs of the chair frame be farther separated than the rear legs.

Simplicity of fabrication of the structural ele-

ments is another advantage of the invention. Each element is a peripherally pre-shaped portion of plywood sheet permanently molded to produce flatwise curves of the plies where desired. Not only is molded plywood a strong, tough material, but a certain amount of desirable resilience is inherent therein; thus a chair frame made according to the present invention has adequate springiness to absorb normally expected shock both within the legs and within the back rest mount, or portion such as 20 in element 17. Of course, a chair frame so constructed may be made more or less springy by varying the character of the plywood. While, in a structure comprising crossed U-shaped elements fitted together by means of engaging rabbets, the leg strength of the frame is not disturbed by small angular play within the rabbets, such play is highly undesirable, and is completely eliminated by securing portion 18 of element 17 to a flush surface of the X-shaped platform by means of at least four screws or other suitable locking devices, one such screw or such device engaging each leg-forming element on both sides of its rabbit, as shown in Fig. 2. Moreover, the seat portion 22 as shown in Fig. 3 may be constructed of lighter weight material than otherwise would be the case, for it need carry but little of the stresses when the chair is occupied; the frame itself, such as shown in Fig. 1, being sufficiently sturdy to carry substantially all of the stresses.

The terms and expressions which have been employed herein are used as terms of description and not of limitation, and there is no intention in the use of such terms and expressions shown and described or portions thereof, but it is recognized that various modifications are possible within the scope of invention claimed.

What is claimed is:

1. A knock down chair frame which comprises two crossed U-shaped integral members of molded plywood, each having a U-shaped longitudinal axis, each of said U-shaped members consisting of more than three plies of wood all of which are molded together with the plies flatwise and parallel with respect to each other and with respect to the U-shaped longitudinal axis of said member and with the grain of each of the plies of each U-shaped member lying lengthwise of said member; each of said U-shaped members having a straight flat intermediate portion and a curved portion at each end of said intermediate portion and a straight tapered portion depending from each of said curved portions, said depending straight portions forming four outwardly slanting legs, the intermediate portion of one of said U-shaped members having a rabbet in the lower surface of its said intermediate portion and the other of said U-shaped members having an oppositely disposed rabbet in the upper surface of its said intermediate portion, said rabbets being fitted together so that said straight intermediate portions form an X-shaped platform having flush upper and lower surfaces which platform is supported by said four legs, all of the plies of said straight intermediate portions lying parallel with said surfaces, another integral member of plywood molded flatwise with respect to the plies thereof and having a flat portion engaging one of the surfaces of said platform and providing a tie member, removable fastening means securing said tie member to said crossed straight intermediate portions of said U-shaped members and holding said three members rigidly.

secured together to prevent wobbling of said U-shaped members.

2. A knock down chair frame which comprises two crossed U-shaped integral members of molded plywood, each having a U-shaped longitudinal axis, each of said U-shaped members consisting of more than three plies of wood all of which are molded together with the plies flatwise and parallel with respect to each other and with respect to the U-shaped longitudinal axis of said member and with the grain of each of the plies of each U-shaped member lying lengthwise of said member, each of said U-shaped members having a straight flat intermediate portion and a curved portion at each end of said intermediate portion and a straight tapered portion depending from each of said curved portions, said depending straight portions forming four outwardly slanting legs, the intermediate portion of one of said U-shaped members having a rabbet in the lower surface of its said intermediate portion and the other of said U-shaped members having an oppositely disposed rabbet in the upper surface of its said intermediate portion, said rabbets being fitted together so that said straight intermediate portions form an X-shaped platform having flush upper and lower surfaces which platform is supported by said four legs, all of the plies of said straight intermediate portions lying parallel with said surfaces, another integral member of plywood molded flatwise with respect to the plies thereof and having a flat portion engaging the under surface of said platform and providing a tie member and having an upright portion forming a mount for a back-rest piece, removable screw means extending through the flat portion of said tie member into said crossed straight intermediate portions of said U-shaped members and holding said three members rigidly secured together to prevent wobbling of said U-shaped members.

3. A knock down chair frame which comprises two crossed U-shaped integral members of molded plywood, each having a U-shaped longitudinal axis, each of said U-shaped members consisting of more than three plies of wood all of which are molded together with the plies flatwise and parallel with respect to each other and with respect to the U-shaped longitudinal axis of said member and with the grain of each of the plies of each U-shaped member lying length-

wise of said member, each of said U-shaped members having a straight flat intermediate portion and a curved portion at each end of said intermediate portion and a straight tapered portion depending from each of said curved portions, said depending straight portions forming four outwardly slanting legs, the intermediate portion of one of said U-shaped members having a rabbet in the lower surface of its said intermediate portion and the other of said U-shaped members having an oppositely disposed rabbet in the upper surface of its said intermediate portion, said rabbets being fitted together so that said straight intermediate portions form an X-shaped platform having flush upper and lower surfaces which platform is supported by said four legs, all of the plies of said straight intermediate portions lying parallel with said surfaces, another integral member of plywood molded flatwise with respect to the plies thereof and having a flat portion engaging the lower surface of said platform and providing a tie member, and having an upright portion forming a mount for a back-rest piece, removable screw means extending through the flat portion of said tie member into said crossed straight intermediate portions of said U-shaped members and holding said three members rigidly secured together to prevent wobbling of said U-shaped members, a seat piece resting upon and removably secured to said platform and a back-rest piece removably secured to said mount.
